W. H. ATWOOD

TIE PRESSER

Filed June 30, 1922

W. H. Atwood

INVENTOR

Leo Hayes

WITNESS:

Victor J. Evans

ATTORNEY

UNITED STATES PATENT OFFICE.

WALTER H. ATWOOD, OF WALDEN, NEW YORK.

TIE PRESSER.

Application filed June 30, 1922. Serial No. 571,876.

To all whom it may concern:

Be it known that I, WALTER H. Atwood, a citizen of the United States, residing at Walden, in the county of Orange and State 5 of New York, have invented new and useful Improvements in Tie Pressers, of which the following is a specification.

This invention relates to a press, the general object of the invention being to provide 10 a means of pressing neck-ties, so as to keep the ties in shape and free of wrinkles without the necessity of ironing them.

Another object of the invention is to provide means whereby a plurality of ties may 15 be held in the press at the same time and also to so arrange the parts that the ties may be easily and quickly removed from and replaced in the press.

The invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote like or corresponding parts throughout the sev- 30 eral views, and in which:—

Figure 1 is a plan view of the device.

Figure 2 is a side view thereof.

Figure 3 is a section on line 3—3 of Figure 1.

Figure 4 is a similar view but showing the clamping bolts in inoperative position.

Figure 5 is a fragmentary plan view showing the bolts in inoperative position.

Figure 6 is a similar view of the top board 40 with the bolts removed.

Figure 7 is a view of one of the middle boards.

In these views, 1 indicates the upper board and 2 the lower board of the clamp or press.

45 A number of middle boards 3 are also included in the invention, over which the ties, shown at A are looped. The boards are prefer- ably of the shape of the ties to be pressed but considerably larger, as shown in Figure 1 in full and dotted lines. The top and bottom boards have their small ends connected to

gether by a spring clip 4 which is fixed to each board by rivets 4' and permits the boards to be moved towards and from each other. The clamping bolts 5 are of L shape 55 with the ends of the long limbs threaded to receive the nuts 6. The short limbs have their extremities bent over and these limbs are flattened as shown at 7. The bolts pass through holes 8 in the bottom board and 60 through notches 9 in the top board and when the bolts are in clamping position the bent extremities engage recesses 10 in the top board, which prevent the bolts from turning while the nuts are being tightened. 65

From the foregoing it will be seen that by loosening the nuts the bolts can be turned until their bent ends face outwardly, as shown in Figures 4 and 5, so that the top board can be lifted off to permit the middle 70 boards and the ties to be removed. When the ties are to be put in the press they are placed on the middle boards and these boards with the ties thereon are placed between the top and bottom boards of the press. The 75 bolts are then swung around so as to place their enlarged extremities in the recesses and the nuts are then tightened to move the outer boards towards each other and thus press the ties between the boards. 80

It is thought from the foregoing descrip- 85 tion that the advantages and novel features of my invention will be readily understood.

I desire it to be understood that I may make changes in the construction and in the 85 combination and arrangement of the several parts, provided that such changes fall within the scope of the appended claim.

Having thus described my invention what I claim as new is:—

A press of the class described, comprising a top board and a bottom board, a spring clip for connecting the boards together at one end, the top board having notches in its side edges and recesses in its upper face, L shaped bolts carried by the bottom board and engaging the notches in the top board, each bolt having a projection on its extremity for engaging a recess when the bolts are in clamping position and nuts on the bolts. 100

In testimony whereof I affix my signature.
WALTER H. ATWOOD.
